COMBINED MINIATURE FLASHLIGHT AND KEYHOLDER

Sidney Schwartz, New York, N.Y., assignor to Bantam-Lite, Inc., New York, N.Y., a corporation of New York

Filed Oct. 20, 1964, Ser. No. 82,245

Term of patent 14 years

(Cl. D48—24)

FIG. 1 is a perspective view of a combined miniature flashlight and keyholder showing my new design, the broken line showing being for illustrative purposes only.

FIGS. 2 and 3 are top and bottom plan views, respectively, thereof.

FIG. 4 is a side elevational view thereof, the opposite side being of similar appearance, and

FIGS. 5 and 6 are rear and front elevational views, respectively, thereof.

I claim:

The ornamental design for a combined miniature flashlight and keyholder, as shown and described.
